UNITED STATES PATENT OFFICE.

ABRAHAM M. MALOUF, OF NEW YORK, N. Y.

GARTER.

Application filed June 9, 1924. Serial No. 718,875.

To all whom it may concern:

Be it known that I, ABRAHAM M. MALOUF, a citizen of the United States, residing at New York, in the county of New York and State of New York, have invented a new and useful Garter, of which the following is a specification.

By way of explanation it may be stated that when the elastic band of a garter is stitched to the pad of the garter, the stitching severs some or all of the elastic strands in the band, and the present invention aims, in view of the foregoing, to provide novel means for connecting the elastic band to the pad without stitching the band and rupturing the elastic strands thereof.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—Figure 1 shows in plane, a portion of a garter embodying the invention; Figure 2 is a section on the line 2—2 of Figure 1; Figure 3 is an enlarged diagrammatic sectional view; Figure 4 is a perspective view showing the connector; Figure 5 is a plan showing a modified connector; Figure 6 is a cross section on the line 6—6 of Figure 5; Figure 7 is a cross section on the line 7—7 of Figure 5; Figure 8 is a plan disclosing a modified form; Figure 9 is a plan showing the connector used in Figure 8; Figure 10 is an elevation wherein the structure of Figure 8 is viewed edgewise; Figure 11 is a section taken on the line 11—11 of Figure 8.

The numeral 1 marks the pad of a garter comprising layers 2 connected by stitching 3. A loop 4 is provided, the ends of the loop extending between the layers of the pad 1 and being held between the layers 2 by the stitching 3. The loop 4 preferably is made of flexible material. The numeral 5 designates a connector, including end bars 6, side bars 7 and an intermediate bar 8 having teeth 9 along one edge, there being a flange

10 projecting from the opposite edge of the intermediate bar, and there being a slot 12 between the intermediate bar 8 and one side bar 7, a slot 14 existing between the intermediate bar 8 and the other side bar 7. One of the side bars 7 is received within the loop 4 which is assembled with the pad 1. The elastic band of the garter is marked by the numeral 15 and is looped about the intermediate bar 8, as shown at 16. The flange 10 of the intermediate bar 8 is bent to overhang the bar 8 as shown at 17 in Figure 3, one end of the band 15 being gripped between the parts 8 and 17 and being held by the part 17 and teeth 9, which are inclined slightly with respect to the intermediate bar 8, the teeth 9 being neither long enough nor sharp enough to penetrate the elastic band 15 and sever the resilient strands thereof.

The device is so constructed that it is unnecessary to stitch the band 15 to the pad 1, to the detriment of the band, as hereinbefore explained. The slot 12 is large enough so that as shown at 18 in Figure 1, there is an appreciable space between the folded portion of the band 15 and the loop 4. As a consequence, the slot 12 is not filled, even approximately, by the looped portion of the elastic band 15, and the device distinctly avoids all disadvantages arising out of a construction in which the folded or looped portion 16 of the band 15, and the loop 4 present an uninterrupted bearing surface. The construction of the device is such that the band 15 may be looped readily as at 16, with respect to the intermediate bar 8.

The connector may be of the form shown in Figures 5, 6 and 7 and denoted generally by the numeral 25. The connector including end bars 26, side bars 27 and an intermediate bar 28, the ends of one side bar 27 being received in a sleeve 29. The parts 26 and 27 preferably are made of a single piece of wire having no sharp edges, whereas the intermediate bar 28 is in the form of a strip provided at its ends with tubular sockets 30 wherein the end bars 26 are securely mounted. The intermediate bar 28 has a longitudinal slot 31, and from one portion of the bar, inclined teeth 32 project into the slot. One end of a flexible element (such as the part 15) may be inserted into slot 31, the flexible element being looped as at 16, in the manner hereinbefore explained.

Passing to the form shown in Figures 8 to 11, the connector is marked by the nu-

meral 35 and includes end bars 36, side bars 37 and 40, and an intermediate bar 38 having teeth 39 along one edge, the other edge of the intermediate bar being supplied with 5 a flange 41. The loop, corresponding to the loop 4, is marked by the numeral 42 and is engaged about the side bar 40. The flange 41 is bent as at 43 to grip one end of the garter band, as hereinbefore explained, the garter band, designated by the numeral 44, being looped and extended in the way hereinbefore set forth. In this form of the invention, the end bars 36 are offset, as shown 10 at 45, so as to decrease the friction between 15 the side bar 37 and the garter band 44.

What is claimed is:

1. In a garter, a pad, a connector comprising side bars, end bars and an intermediate bar provided along one edge with 20 teeth and equipped along its opposite edge with a bendable flange, a loop carried by the pad and receiving one side bar of the connector, and a band looped about the intermediate bar, the flange being bent to overhang the intermediate bar, one end of the 25 band extending between the flange and the intermediate bar and being held by the flange on the teeth, the intermediate bar being spaced far enough from said one side 30 bar to leave an opening of appreciable size

between the looped portion of the band and the loop, thereby facilitating the looping of the band about the intermediate bar.

2. In a garter, a pad, a connector comprising side bars, end bars, and an intermediate bar having teeth, a loop carried by the pad and receiving one side bar of the connector, and a band looped about the intermediate bar and engaged by the teeth, the intermediate bar being spaced far enough from said one side bar to leave an opening of appreciable size between the looped portion of the band and the loop, thereby facilitating the looping of the band about the intermediate bar. 45

3. A device of the class described, constructed as set forth in claim 1, and further characterized by the fact that the band passes beneath one side bar, the end bars being offset, so that the side bars are not in 50 the same plane, thereby to lessen the friction between the said side bar and the band.

In testimony that I claim the foregoing as my own. I have hereto affixed my signature in the presence of two witnesses.

ABRAHAM M. MALOUF.

Witnesses:

MOLLIE MILLER,
SAID JOSEPH AKEL.
